US0D1008127S

(12) **United States Design Patent** (10) **Patent No.:** **US D1,008,127 S**
(45) **Date of Patent:** **** Dec. 19, 2023**

(54) **VEHICLE FENDER**

- (71) Applicant: **Oshkosh Corporation**, Oshkosh, WI (US)
(72) Inventors: **Jesse Gander**, Larsen, WI (US); **Christopher Yakes**, Oshkosh, WI (US)
(73) Assignee: **Oshkosh Corporation**, Oshkosh, WI (US)
(**) Term: **15 Years**
(21) Appl. No.: **29/830,408**
(22) Filed: **Mar. 11, 2022**

Related U.S. Application Data

(57) **CLAIM**

We claim the ornamental design for a vehicle fender, as shown and described.

DESCRIPTION

FIG. 1 is a front perspective view of the claimed design; FIG. 2 is a front view of the claimed design; FIG. 3 is a rear view of the claimed design; FIG. 4 is a left side view of the claimed design; FIG. 5 is a right side view of the claimed design; FIG. 6 is a top view of the claimed design; and, FIG. 7 is a bottom view of the claimed design. Evenly-spaced broken lines depict unclaimed environmental subject matter. Dash-dot broken lines depict unclaimed boundaries of the claimed design.

1 Claim, 7 Drawing Sheets

Related U.S. Application Data

May 18, 2017, now Pat. No. 10,434,995, which is a continuation of application No. 14/724,279, filed on May 28, 2015, now Pat. No. 9,656,640, said application No. 29/621,958 is a continuation of application No. 14/612,100, filed on Feb. 2, 2015, now Pat. No. 9,829,282, said application No. 14/724,279 is a continuation of application No. 13/841,686, filed on Mar. 15, 2013, now Pat. No. 9,045,014, said application No. 14/612,100 is a continuation of application No. 13/629,009, filed on Sep. 27, 2012, now Pat. No. 8,943,946.

- (60) Provisional application No. 61/615,812, filed on Mar. 26, 2012, provisional application No. 61/539,838, filed on Sep. 27, 2011.
